Cornelia C. Billings

UNITED STATES PATENT OFFICE.

LOUIS STEINBERGER, OF BROOKLYN, NEW YORK.

SOUND-AMPLIFYING TRANSMITTER.

Application filed December 24, 1924. Serial No. 757,803.

This invention relates to sound conveying transmitting and amplifying structures, commonly known as loud speakers, specially applicable to radio equipment, talking machines, telephones, megaphones, speaking tubes, acoustic and musical instruments.

The object of the invention is to provide a means for amplifying and transmitting sound waves without distortion, and thus retain all the original beauty of musical and other tones and the natural qualities of the human voice.

Referring to the drawings forming a part of this specification:

15 Fig. 1 is a front view of the device embodying my invention,

Fig. 2 is a section on line 2—2 of Fig. 1,

Fig. 3 is a plan of the sound conveying device used in one form of my invention,

20 Fig. 4 is a vertical section on line 4—4 of Fig. 3, and

Fig. 5 is a section similar to Fig. 2 of a modified form of the invention.

Fig. 6 is a section on line 6—6 of Fig. 1.

25 In the drawings A is the body of the device preferably formed from moldable material, molded into the shape shown. B is the neck portion through which the sounds are conveyed direct to the sound reflecting surface

30 20. C is the base and U the sound unit of usual construction.

In carrying out my invention, I provide a passageway 10 in the neck portion B of the device A for the sound waves which is of tapering form and of funnel shape, circular in horizontal cross section only at the point of attachment to the transmitting unit U, the cross section above this point having a greater dimension on one axis or in one direction than on the other. The upper portion of the passageway is provided with diverging walls, the side walls 12 and 13 being flat and the end walls 14 and 15 curved or rounded. The entire shape of this passageway may be described as a curve of unequal dimensions in horizontal cross section. An inclined flat reflecting surface 20 is provided directly above this passageway which surface receives directly the sound waves as they emanate from the transmitting unit U through the amplifying sound conveying passageway 10 and directly transmits all the sound waves into space without distortion.

The inclined flat sound reflecting surface 20 should at its base portion have the same

width as the width of the upper end of the tapering sound amplifying passageway and the width of the upper portion of the inclined sound reflecting surface is preferably greater than that of the lower portion thereof.

60

By means of this construction sound waves are transmitted with full volume of clear and undistorted tones.

The side walls 21 and 22 and the bottom wall 23 adjacent the back sound reflecting surface 20 of the amplifier are each substantially flat, the side walls diverging outwardly from the flat back reflecting surface 20 and the bottom wall from the front of the passageway 10, as clearly shown in the drawing.

70

It is desirable to form the sound conveying passageway by utilizing a metallic funnel F, which is molded into the sound amplifier, as shown, (Figs. 1 and 2) the upper edge at 30 engaging a lip 31 formed in the wall of the amplifier A in order to hold the funnel F securely in place. The circular end of the funnel is screwthreaded at 32 so that a screwthreaded connection may be formed at 33 with the unit U, and a space S is formed in the bottom of the amplifier A for the reception of the unit, a plate 34 being secured to the base C in any suitable way to form the lower wall of said space S.

80

The utilization of the funnel shaped device F, which is preferably of metal, may be dispensed with and the sound passageway 10 may be formed directly in the neck B of the sound amplifier A, as shown in Fig. 5, the shape of the passageway being the same as heretofore described when the passageway is metallic lined by utilizing the funnel F illustrated in Figs. 3 and 4. In this modified construction, however, it is desirable to mold at the lower end of the device a ferrule 40 circular in horizontal cross section and screw-threaded at 41, so as to receive co-acting screwthreads 42 on the unit in order to secure the unit in place. In other respects, the structure shown in Fig. 5 is the same as that shown in Figs. 1 and 2.

90

95 As changes of construction could be made within the scope of my invention, it is intended that all matter contained in the above description or shown in the accompanying drawings be interpreted as illustrative and not in a limiting sense.

100

Having thus described my invention what I claim as new and desire to secure by Letters Patent is:

110

1. In a device of the kind described, a sound conducting structure provided with an inclined flat sound reflecting surface, the said surface being connected directly with an enclosed sound conveying passageway having tapering sides, two opposing sides being flat and the opposing ends rounded. 25
2. In a device of the kind described, a metallic funnel shaped element forming walls 10 of a sound conveyor, the horizontal cross section of said element having a greater dimension in one direction than in the other and the walls of the said funnel shaped element being provided with a base rounded in cross 15 section, a flaring portion having flat sides and rounded ends, the surfaces of the sides and ends merging into each other.
3. In a device of the kind described, an inclined sound amplifying surface connected 20 with a sound conveying passageway having tapering sides, the horizontal cross section of said passageway having a greater dimension in one axis than on the other.
4. In a device of the kind described, an inclined sound amplifying and reflecting surface connected with a sound conveying passageway, having tapering sides, two of the opposing sides thereof being substantially flat. 30
5. In a device of the kind described, a sound conveying structure provided with an inclined flat sound reflecting surface, the upper portion of said reflecting surface being of greater width than the lower portion, the lower portion merging into and being connected with an enclosed sound conveying passageway. 35
6. In a device of the kind described, a sound conveying structure provided with an inclined flat sound reflecting surface, said surface being connected with a single enclosed sound conveying passageway of tapering form the dimension of the horizontal cross section of said passageway being greater in one direction than in the other. 40

LOUIS STEINBERGER.
